Des. 188,695
Patented Aug. 23, 1960

188,695

SHIRT FOLDING BOARD

Helen M. Ziegler, 5 De Forest Road, Wilton, Conn.

Filed Apr. 22, 1959, Ser. No. 55,609

Term of patent 14 years

(Cl. D49—1)

FIG. 1

FIG. 2

FIG. 3

Fig. 1 is a perspective view of a shirt folding board, embodying my new design;

Fig. 2 is an elevational view taken from the top of Fig. 1, and;

Fig. 3 is a side elevational view thereof.

I claim:

The ornamental design for a shirt folding board, as shown.
